UNITED STATES PATENT OFFICE.

BENJAMIN J. CRAGGY, OF MANCHESTER, NEW HAMPSHIRE, ASSIGNOR OF TWO-THIRDS TO G. A. OLZENDAM AND E. O. WILSON, OF SAME PLACE.

WASTE-END CONVEYER FOR CARDING-MACHINES.

SPECIFICATION forming part of Letters Patent No. 467,888, dated January 26, 1892.

Application filed September 14, 1891. Serial No. 405,606. (No model.)

To all whom it may concern:

Be it known that I, BENJAMIN J. CRAGGY, of Manchester, in the county of Hillsborough and State of New Hampshire, have invented 5 certain new and useful Improvements in Waste-End Conveyers for Carding-Machines, of which the following is a specification.

My invention has reference to wool-carding machines generally, and is particularly adapted for use in connection with machines in which what is commonly known as the "Apperly feed" is employed.

In machines of the kind mentioned the two side or end strands of roving delivered from the 15 condensing-rolls are irregular and defective, for the reason that they are formed from the irregular looped ends of the drawing deposited in diagonal lines upon the endless traveling apron, which supplies staple to the second 20 breaker.

It is the object of the invention to provide simple and efficient means whereby the aforesaid defective strands of roving may be taken from the condensing-rolls and carried back to 25 the feed-box and delivered therein to be re-carded.

The invention will first be described with reference to the accompanying drawings, forming a part of this specification, and then 30 be pointed out in the claims.

Of the said drawings, Figure 1 is a side elevation of a set of cards such as are commonly used in woolen-mills, with my invention applied thereto, portions of the latter being represented as broken away. Fig. 2 is a diagram showing the condensing-rolls and some other adjuncts of the carding-machine at the delivery end thereof, parts being represented as in 35 section and other parts as broken out.

Like letters of reference designate like parts or features, as the case may be, in both views.

In representing a carding-engine I have, for the sake of clearness of explanation, omitted to portray more of the parts than is necessary.

In the drawings, having reference to Fig. 1, *a* designates what may be supposed to be a Bramwell or other suitable feed-box, from which the stock or staple is delivered upon 50 the feed-table *b* and supplied to the first breaker, of which *c* is the main cylinder.

d is the doffer-cylinder, which takes the staple from the cylinder *c* and from which it is in turn taken by a vibrating doffer-comb (not shown) of common construction in the form 55 of a loosely-formed rope and passed through the drawing-rolls *e*, whence it passes upward and over overhead rolls *f* and is delivered to what is known to carding artisans as the "Apperly feed" *g*.

The Apperly feed consists of mechanism which deposits the drawing received from the overhead rolls in diagonal lines upon an endless apron which travels toward and supplies staple to what is herein shown as the second 60 breaker. To further explain, the mechanism of the Apperly feed *g* operates to lay the drawing upon the said endless apron, so that its course will be back and forth from side to side of the apron in lines oblique to its line of 65 travel, loops or bends being formed at the sides at each return point of the drawings.

h designates the main cylinder of the second breaker, which operates upon the stock received from the feed *f*, and from the second breaker the staple is conveyed in the usual 70 way to the finishing-card, of which *i* is the main cylinder and *j* the doffers, which remove the stock from the main cylinder *i* and deliver it to the condensing-rolls *k*. The 75 amount of stock contained in the looped ends of the drawing laid upon the apron *f* is uneven, and the position of the said loops upon the apron is more or less irregular, and as a consequence the edges of the sheet of material on the main cylinder *i* is ragged and irregular, making the threads of roving formed therefrom unsuited for use on spinning-frames. The said threads are therefore collected as waste and carried back to the feed- 80 box to be re-carded; and my invention consists of means for accomplishing this function of returning the waste from the condensing-rolls to the feed-box.

In Fig. 2 I have shown the two banks of 85 condensing-rolls at the delivery end of the machine, *l* designating the perfect threads of roving and *m* the imperfect or waste threads which are formed from the sides of the bat or sheet of staple doffed from the finishing-card. 90

n designates a tube or pipe, the open end of which is arranged at the point at which the

thread of roving *m* is delivered from the one bank of condensing-rolls, and *o* is a similar tube, the open end of which is arranged to receive therein the waste or imperfect roving 5 coming from the other bank of condensing-rolls. The two tubes *n o* converge at the point *p*, where they connect with a single pipe *q*, which communicates with a blast fan or blower *r*. *s* is a delivery tube or pipe leading 10 from the blast-fan back to the feed-box *a*, as is most clearly shown in Fig. 1.

With this construction and arrangement of parts the waste roving will be drawn or sucked through the tubes *n o p* by the blast-fan and forced through the delivery-tube *s* to a suitable point in the feed-box without injury to 15 the staple and with the expenditure of little power or force.

The tubes or pipes between the ends of the 20 machine, as also the blast-fan, may be located beneath the floor upon which the machine stands, or extend overhead above the machine, or be otherwise suitably positioned, as circumstances may suggest or require.

25 My invention is not confined to machines in which the Apperly feed is employed in connection with the second breaker, as the said feed may as well be used, as is frequently done, in connection with the finisher, and, 30 furthermore, the delivery-pipe, instead of extending to the feed-box, may extend to a waste-box, the picker-room, or other place or point. By my improvement the waste ends are 35 automatically conveyed from the carding-machine to a distant point with the expenditure

of little power and without injury to the staple, and, moreover, the conveying pipes or tubes can be arranged in places entirely out of the way of other machinery, the operatives, &c.

Having thus explained the nature of my invention and described a way of constructing and using the same, though without attempting to set forth all of the forms in which it may be made or all of its modes of use, I declare 45 that what I claim is—

1. In a carding-machine, the combination, with the condensing-rolls, of a blast-fan, pipes or tubes extending between the points of delivery of the waste ends and the said blast-fan, and a single pipe extending from the blast-fan to a receptacle at a distant point, as set forth.

2. In a carding-machine, the combination, with the feed-box, condensing-rolls, and intermediate carding and feeding mechanism, of pipes or tubes *n* and *o*, extending from the point of delivery of the extreme side threads of roving, a blast-fan with which said pipes communicate, and a single delivery-pipe extending from the blast-fan to the feed-box or other receptacle or point, as set forth.

In testimony whereof I have signed my name to this specification, in the presence of two subscribing witnesses, this 10th day of September, A. D. 1891.

BENJAMIN J. CRAGGY.
